UNITED STATES PATENT OFFICE.

VINTON E. SISSON, OF CHICAGO, ILLINOIS, ASSIGNOR TO WALTER P. MURPHY, OF CHICAGO, ILLINOIS.

OPERATING DEVICE FOR CAR COUPLERS.

Application filed January 27, 1920. Serial No. 354,450.

To all whom it may concern:

Be it known that I, VINTON E. SISSON, a citizen of the United States, residing at Chicago, in the county of Cook and State 5 of Illinois, have invented certain new and useful Improvements in Operating Devices for Car Couplers, of which the following is a specification.

In the drawing Figure 1 is a perspective 10 view of the end of a car structure, broken away, with my invention applied thereto.

Figure 2 is a front elevation of the same.

Figure 3 is an enlarged detail sectional view on line 3—3 Figure 2 through the 15 levers and their connections.

Figure 4 is a top plan view of Figure 2.

Figures 5 and 6 are diagrammatical views.

Figure 7 is a perspective view of the hand 20 lever, one end being broken away.

Since the adoption of the new M. C. B. 25 coupler, which is materially heavier than the couplers heretofore in use, it has been found necessary to increase the power in some types of levers, or operating devices 30 for car couplers. Many experiments have been made with this end in view but, in view of the fact that the Federal regulations prohibit the outer end of the operating lever from coming nearer than "17 or 18" inches 35 from the top of the rail, it will be understood that many difficulties had to be surmounted to obtain the increased leverage and at the same time keep within the limits described by the Federal regulations.

The objects of my invention are to so construct and mount the members of the release rigging that any desired lifting power may be obtained to operate the coupler.

A further object of my invention is to 40 so mount the members of the operating device relatively to each other so as to prevent an abnormal upward movement of the inner, or pin operating lever, whereby injury to the operator is prevented in case 45 of a broken coupler mechanism.

A further object of my invention is to so 50 relatively mount and engage the levers of the rigging to prevent an abnormal downward movement of the hand operating lever whereby the operating lever is prevented from coming closer to the rail than the distance allowed by law.

A further object of my invention is to 55 relatively locate the fulcrums of the two

levers and construct the inner end of the hand operating lever in such a manner as to limit the downward movement of the pin lever in case of a broken coupler head or carry iron, whereby the operating device will support the coupler and prevent 60 it from falling on the track and causing derailment.

A further object of my invention is to so locate the fulcrum points of the two levers and their operative connection so as 65 to reduce the relative motion between the two levers at their operative connection to a minimum thereby reducing the friction between the working parts; and with these and other objects in view, my invention consists of the parts and combination of parts 70 as will be hereinafter more fully set forth.

The reference numeral 1 designates a car structure, 2 a coupler and 3 the coupler lock pin all of which may be of any approved 75 construction.

The hand operating lever 4 of my improved operating device is of such construction that when mounted on a car the outer end portion sags downwardly whereby 80 it is adapted to be engaged and operated by the hand or foot of trainman. The hand or outer operating lever is deflected upwardly as at 5 and forwardly as at 6 at its inner end, the portion 6 extending in the 85 same vertical plane as the main body portion of the lever. This inner end of the lever 4 is provided with an opening 7 for a fulcrum pin 8, and with a fulcrum pin 9 for the inner pin lever. At the juncture of 90 the extension 5 and the lever 4, I form a rounded bearing 10, which will be herein-after referred to.

The inner or pin lifting lever 12 has a reduced inner end 13 which is adapted to 95 freely slide in the eye of the coupler lock pin 3 to accommodate service movements of the coupler without imposing strain upon the parts; said portion terminating in hook 14 which prevents accidental disengagement 100 of the lever from the lock pin. The pin lever 12 is pivoted at its outer end on a pin 15. The pin operating lever 12 is provided substantially near its fulcrum pin 15 with an elongated slot 17 through which 105 the pin 9 on the inner end of the lever 4 projects, said pin 9 being provided at its outer end with an upwardly extending hook

18 to prevent the lever 12 from falling to the track in the event that it becomes disengaged from its pivot pin 15.

It will be noted from the drawing that 5 the fulcrum pins 8, 9, and 15 are positioned in the same longitudinal plane. This is shown more clearly in Figure 5. The object of this disposition of these pins is to increase leverage and at the same time reduce 10 friction. By reason of this disposition of these pins the pin 9 is required to move a shorter distance in the slot 17 of the lever 12 to obtain the required elevation of the inner end of the pin lifting lever to move 15 the lock pin 3. A 12 inch movement of the end of the hand lever 4 will raise the coupler lock pin 3, through the lever 12, seven and one quarter inches and downward pressure of approximately one hundred 20 pounds on the hand lever gives 165 pounds upward pressure on the coupler lock. Of course any desired power, or travel, can be obtained by adjusting the relative position of the fulcrum pins. The movement of 25 the pin 9 in the slot 17 of the pin lever 12 is less than one quarter inch, as a result of locating the pins 8, 9, and 15 in the same, or substantially the same, longitudinal plane. This limited movement is of importance as 30 it reduces the friction between the two levers to a minimum.

The pin and slot connection between the two levers limits the upward movement of the pin lever 12, thereby preventing injury 35 to the operator in case of the pin lever 12 becoming broken. This pin and slot connection also limits the downward movement of the hand lever whereby the outer end of the hand lever is prevented from coming 40 closer to the rail than is allowed by law.

The location of the two fulcrum pins 15 and 8 and the peculiar formation of the inner end of the hand lever 4 limits the downward movement of the pin lever 12 in 45 this wise; in case of broken coupler head or carry iron the weight of the coupler is thrown on the uncoupling levers whereby the coupler is prevented from falling on the track which would result in derailment. 50 Under such conditions the pin lifting lever will move downward at its inner end until the bearing 10 of the hand lever 4 engages

with the fulcrum 15, thereby preventing the inner end of the pin lever 12 moving any further downward, the pin 15 acting as a 55 stop to prevent further upward movement of the hand lever while the pin 9 prevents further downward movement of the pin lever 12.

What I claim is:—

1. In a release rigging for car couplers, the combination with a pin lifting lever pivotally mounted at its outer end to a car, and a hand operating lever pivotally mounted intermediate its ends to a car at a point intermediate the coupler and the pivot of the pin lever, whereby the pivot of the pin lever acts as a stop to limit the upward movement of the hand lever, and an operative connection between said levers. 60

2. In a release rigging for car couplers, the combination with a pin lifting lever pivotally mounted at its outer end to a car, and an operating lever pivotally mounted intermediate its ends to a car, and an operative connection between the two levers, one of said pivots functioning as a stop to limit the movement of said levers in the event of the breaking of the coupler supporting element; whereby the coupler is prevented 75 from falling to the track. 80

3. In a release rigging for car couplers, the combination with an operating lever, of the pin lifting lever fulcrumed on the car, and slidably connected to the operating lever, the fulcrum of the operating lever being positioned between the fulcrum of the pin lever and the connection between the levers, the device having both fulcrums and connection between the two levers in the 90 same horizontal plane. 85

4. In a release rigging for car couplers, a pin lifting lever fulcrumed to the car, an operating lever fulcrumed to the car and loosely attached to the pin lifting lever, and so positioned that the fulcrum of the pin lifting lever limits the movement of the outer end of the operating lever, and the connection to the pin lifting lever limits the movement of the inner end of the operating lever, the device having the two fulcrums and the connection between the levers all in the same horizontal plane. 95 100

VINTON E. SISSON.
